UNITED STATES PATENT OFFICE.

CESARE BARBIERI, OF NEW YORK, N. Y., ASSIGNOR TO THE VORTEX MFG. CO., OF CHICAGO, ILLINOIS, A CORPORATION OF ILLINOIS.

CONICAL PAPER CUP AND PROCESS FOR MAKING THE SAME.

Application filed February 8, 1923. Serial No. 617,671.

This invention is for an improvement in cups of the type shown in the reissued Patent No. 15,381, granted June 22, 1922, to David F. Curtin. Cups of this type have hitherto been made of paper which is rendered waterproof by being coated with paraffin, wax or other suitable material. One objection to cups so made is that when packed in nested form, the paraffin is apt to soften under the action of a warm climate and cause the cups to adhere so that the nest becomes a united mass. One way of preventing this is illustrated in his Patent #1,413,460, granted April 18, 1922, but this way involves the use of an extra piece of paper and requires several additional operations in the process of making the cup.

It is an object of the present invention to produce a cup which can be stacked in a nest without danger of becoming attached to the other cups in the nest.

It is a further object of the present invention to produce a cup of paper which is not coated, but is rendered waterproof in some other way. The usual kinds of adhesive, such as glue and mucilage, cannot be readily made to adhere with certainty to waterproofed paper. When paraffined paper is used and the cementitious material is melted paraffin, it is necessary to keep the paper nearly, if not quite, to the point where the paraffin will liquefy in order to insure good union between the overlapping parts of the cup. This invention contemplates the use of a cementitious material which, when but slightly heated, will adhere strongly to the waterproofed paper.

Cups made of paraffined paper according to the teaching of the above-mentioned reissued patent are not very firmly joined along the overlap or seam, so that a very little rough handling is sufficient to cause the cup to unwrap. One reason for this is that the springiness of the paper causes the outermost convolution of the cup to come away from the body of the cup while the cup is being formed. The cup is formed by two revolving cones, one inside and one outside of the cup. The pressure of these cones against the paper blank is along one element of the conical paper cup. The paper cup revolves between the pressing cones. This motion may be conveniently described by saying that the element of the cone along which the pressure of these rollers is applied travels around the

paper cup. At the moment that this traveling element leaves the edge of the outer convolution, the part of this convolution between said edge and the rollers, trying to straighten itself, tends to lift this convolution from the cup. There is a relatively large body of stiff paper tending to lift this convolution, while only the comparatively feeble holding action of the hot paraffin opposes this tendency. For this reason, even when the cups are rotated a number of times between the conical rollers during the act of making the cup, the joint formed is not very good.

It is another object of the present invention to materially lessen the area of the paper which is tending to lift the outermost convolution from the body of the cup, so that the lifting action will separate the outer convolution less rapidly. This will enable the pressing rollers to reapply their pressure before the separation is actually accomplished and thus a firm joint may be obtained.

It is a further object of this invention to leave the edge of the outermost convolution free from the cup for a short distance so that a small area of the paper near the point of the cup will spring a slight distance away from the cup. The small portion of lifted paper thus obtained will act as a cushioning device when the cups are arranged in stacks and so will keep the cups slightly separated from one another. This prevents the cups from coalescing into a mass. Moreover, the fact that the cups are made of waterproof paper which is not coated means that the outer surface of the cup is not covered with a substance likely to soften under warm climatic conditions and so the tendency of the cups to become cemented together is avoided.

It is a further object of this invention to apply cementitious material to the blank from which the cup is formed in such a position that when the cup is formed the desired free portion of paper will result, and also in such a position that when the cementitious material spreads under the action of the pressing rollers it will assist in sealing the point of the cup.

It is a further object of this invention to form a blank for a cup of the class described which shall permit the several results just described to be accomplished without requiring any undue accuracy of manipulation.

It is a further object of this invention to apply the cementitious material in the form of a patch with a recess therein which will accommodate the grippers that handle the 5 blank in making the cup.

It is a further object of this invention to so position said recess that the diminished area of cementitious material will occur on that portion of the blank which, in the finished cup, is an intermediate convolution. 10

Other and further important objects of this invention will be apparent from the disclosures in the specification and the accompanying drawings.

15 The invention (in a preferred form) is illustrated in the drawings and hereinafter more fully described.

On the drawings:

Figure 1 is a side view of the cup.

20 Figure 2 is a bottom view.

Figure 3 is a top view.

Figure 4 is a view of the blank from which the cup is formed.

As shown on the drawings:

25 The cup consists of a cone 10, made by coiling up a blank so that it has an overlap or seam which presents an outer edge 11 and an inner edge 12. The outer edge 11, as is best seen in Figure 2, winds about the cup, 30 but the inner edge, as seen in Figure 3, is only slightly curved and is nearly coincident with an element of the cone.

The blank from which the cup is made has an arcuate edge 13 which makes the 35 mouth of the cup and a very nearly radial slightly curved edge 14 which appears in the finished cup as the inner edge 12 of the seam. The edge 14 converges with the other seam-forming edge 15. The other converging edge 15 of the blank is approximately 40 straight and stands at a considerable angle with the radius to its outer end. The inner end of the edge 15 merges with the curved edge 16 of a projection.

45 The edges 16 and 15 combine to make the outer edge 11 of the seam, as shown in Figure 2. Where the edge 16 merges with the edge 15, the straight line 15 is approximately tangential to the curve 16, so that no

50 abrupt change in direction occurs. From this merging point 17 to a point 18, rather more than a quarter of a circumference away, the curve 16 is of approximately constant radius, and from the point 18 to the

55 meeting of the projection with the edge 14 the edge 16 is again of approximately constant radius, but this radius is smaller than that of the first-described part of the curve 16, so that the periphery of the projection as a whole has a curved edge whose radius 60 of curvature increases as we go from the edge 14 to the edge 15.

The curved edge 16 meets the curved edge 65 14 at a point 19, the two curves making a very acute angle with each other. In fact,

they may very well have a common tangent at this point, which would have the direction indicated by the broken line to the point *a*. This character of the meeting point of the edges 14 and 16 is represented, when 70 the blank is made in a commercial way by cutting with a die, by a slit or cut extending for a short distance inward from the meeting point of the edges and so narrow that it is made by a single cutting edge in the die. 75 The blank is made of paper which is waterproofed by being impregnated with wax, paraffin solution, or some other waterproofing agent. The waterproofing agent, however, is not coated onto the outer surfaces of 80 the paper but is embodied into the material of the paper itself. The paper surface is left with so little paraffin, wax or other like substance that it cannot be rendered adhesive by merely heating it. The seam is 85 united by means of an adhesive or other cementitious material of a kind which will unite with the waterproofed paper when heated, although when cold it acts as do most adhesives when applied to paraffined paper, gathering into globules instead of uniting with the surface.

Adhesive is applied to the blank by means of a die or other suitable mechanism in a patch of the form illustrated at 20. Preferably the central part of the area to be outlined by the adhesive is left uncovered so that the adhesive is in the form of a patch which surrounds an area 21 of nonadhesive paper. One edge 22 of the patch of adhesive is approximately parallel to the radius which separates the sector-shaped main body of the blank from the part that extends beyond this sector. The edge 23 of the patch of adhesive material is at an angle with the edge 22 and extends approximately parallel to the straight part 15 of the non-radial edge of the blank. Opposite the point 17, where the straight edge 15 merges with the curved edge 16, the adhesive patch also has a curve in its edge so as to keep the margin between the cementitious material and the edge of the blank of approximately constant width. The patch follows the curve of the blank throughout, except as noted below, so that this margin is of substantially constant width with these exceptions.

The first exception is that a bay 24 is left in the patch of cementitious material to accommodate the grippers which must grasp the blank when it is being formed into a cup and which must not become covered with the cementing material. This bay is opposite that part of the curve 16 which lies diametrically opposite the middle portion of the curved edge 13.

A third variation in the size of the margin is found at the point 19 where the edges 14 and 16 come together. This point is to be the apex of the cup, and is the corner of the

curvature of the edge 13. The cementitious material approaches much nearer to this point than it does to any other part of the edge of the blank.

5 In forming the blank into a cup, it is coiled or rolled upon itself, as is clearly seen from Figures 1 and 2. The coiling or forming is done by two conical rollers acting upon the blank, one within and one without 10 the cup. These rollers rotate and so cause the cup to rotate between them. It will be obvious, therefore, that the two forming rollers contact the blank upon an element 15 of the cone. Pressure is applied to the cup along a single line at a time, but this line includes a number of lines upon the blank because the cup is made up of superposed convolutions. Thus in Figure 4 the line *a* represents the location of the pressure of the 20 forming rollers upon the blank at the moment that the last of the projection 16 is just escaping from the pressing rollers. The projection is, however, wound about the cup so that at the same moment the line *b* and the 25 line *c* are superposed upon each other and upon the line *a* and are each receiving pressure at this instant. The portion of the blank between the lines *a* and *b* constitutes the innermost convolution of the cup. The 30 portion of the blank between the lines *b* and *c* constitutes the intermediate convolution, and the portion of the blank between line *c* and the extremity of the projection constitutes the outermost convolution. 35 It will be observed that the portion between the lines *b* and *c*, when the cup is formed, is between the converging ends of the two edges 14 and 16 and so assists in closing the cup at the point 19. The pressure of the 40 forming rollers against the overlapping part of the blank will cause the cementitious material to flow somewhat so that it will approach the edge of the blank, but at no point except 19 will it actually reach the 45 edge. At the point 19 the adhesive material will assist in sealing the apex of the cup. Because the angle between the curves 16 and 14 at this point is very small so that it practically forms a mere split, a considerable 50 obstacle is presented to the flow of adhesive through the cup at its apex. The part of the blank between the lines *b* and *c* and near the point 19 is crowded into the slit between the ends of the edges 14 and 16 and so makes 55 a tight joint through which the adhesive cannot easily get. For this reason, even when the outline of the blank and the position of the parts with cementitious material thereon vary slightly, as they do in manufacturing, it will still be unusual for any 60 cementitious material to appear on the exterior of the cup.

Along almost all of the margin the flow of the cementitious material under the pressure will cause the material to come nearly

but not quite to the edge of the blank. At the point 25 some little width of paper will be left uncemented. In the finished cup, this makes a portion that does not lie down flat against the body of the cup, but stands 70 slightly raised therefrom due to the resilience or stiffness of the paper. This gives a slight springy projection at the point of the cup so that when the cups are nested they cannot fit too closely in contact with one another. The likelihood of the cups adhering to one another while in nested form is thus very materially lessened. The fact that the outer surface of the cup is not coated with paraffin, wax or other material that will become adhesive in a warm climate also assists in preventing the adhesion of the cups in nested form. These two factors together render such adhesion exceedingly unlikely to occur.

The bay 24 left in the patch of adhesive material in order to accommodate the grippers of the machine does not materially lessen the strength of the resulting cup because it occurs in the intermediate convolution and not in either the interior or exterior one. Consequently the portion of the cup which is left with less adhesive because of this bay is reinforced both inside and outside with other convolutions which have abundant adhesive.

The cup which results from this method of manufacture is capable of withstanding much more rough treatment than cups heretofore made because of the firm character of the seam. This firm character is due, at least in part, to the fact that only the portion of the blank between the line *c* and the upper end of the projection as shown in Figure 4 will yield to the springing action of the paper when the rollers pass off of the edge of the projection. A considerable portion of the area of this portion constitutes that part of the outer convolution which is not fastened in the finished cup. The springing character of this part does not tend to diminish the strength of the joint and the remainder of said portion being a small area of paper acts only very slowly against the holding action of the adhesive. The cup is rapidly rotated by the rollers. Consequently the pressure of the rollers against the portion 25 of the parts of adhesive is repeated before the paper in its straightening or springing action has had time to pull the joint apart. Therefore, the joint receives repeated pressure while the effect of the first pressure is still present. The paper is therefore held in the proper conical form long enough for the joint to effectively set. Moreover, all of the adhesive between the lines *b* and *c* and all of the adhesive between line *b* and the left of Figure 4 are 120 permanently held in place during the whole of the action of the rollers so that all but 130

a very small part of the adhesive has had a chance to firmly set before the action of the rollers is ended.

I am aware that numerous details of construction may be varied through a wide range without departing from the principles of this invention, and I therefore do not purpose limiting the patent granted otherwise than necessitated by the prior art.

10. I claim as my invention:

11. A blank for paper cups, having an arcuate and two converging edges, one converging edge being offset with respect to the center of the arcuate edge, the other converging edge leading from substantially said center but not offset therefrom, and a projection between said converging edges, the edge of which forms a continuous curve therebetween.

12. In a paper cup of the convolute conical type, cementitious material between overlapping convolutions, the outer convolution having near the point of the cone a margin free from cementitious material whereby said margin is free to spring outward from the cup.

13. A conical paper cup having convolutions, the outermost convolution extending less distance from the point than those within and being free from the body of the cup for a fraction of a turn.

14. A conical paper cup having convolutions, and an outwardly springing paper projection adjacent the point whereby when nested said cups are resiliently held apart.

15. The method of forming a paper cup which consists in shaping a blank from non-coated waterproof paper, applying a cementitious material to one face of the parts of said blank which are intended to overlap, said applied material not extending to the edges of the blank, forming the blank into

a convoluted conical cup, exerting pressure on the overlapping parts of the cup whereby the cementitious material is forced towards but not beyond the edges of said blank, and permitting the uncemented margin portion near the point of the cup to spring away.

16. The method of forming a paper cup which consists in shaping a blank from non-coated waterproof paper, applying a cementitious material which will adhere to said paper only when heated, to one face of the parts of said blank which are intended to overlap, said applied material not extending to the edges of the blank, forming the blank into a convoluted conical cup, exerting pressure on the overlapping parts of the cup by heated tools whereby the cementitious material is caused to adhere to the paper and is forced towards but not beyond the edge of said blank, and permitting the uncemented margin portion near the point of the cup to spring away.

17. The method of forming a conical cup between rollers which consists in applying cementitious material to the parts of the paper blank intended to overlap, said application stopping short of the edge of said parts, rolling the blank into a cone with overlying convolutions, pressing said convolutions between said rollers as the cone turns and permitting the edge of the outermost of said convolutions to spring away from the body of the cup under the influence of the stiffness of the paper whereby the innermost convolution will be unattached and the next convolution within for at least a quarter of the way around the cup.

In testimony whereof I have hereunto subscribed my name.

CESARE BARBIERI.
